UNITED STATES PATENT OFFICE.

LEONID A. DUNAJEFF, OF NEW YORK, N. Y.

PIPE-MAKING MACHINE.

Application filed February 15, 1921. Serial No. 445,127.

To all whom it may concern:

Be it known that I, LEONID A. DUNAJEFF, citizen of Russia, and resident of New York, in the county of New York and State of New York, have invented certain new and useful Improvements in Pipe-Making Machines, of which the following is a specification.

My invention relates to the pipe-making machines and has a particular reference to 10 the machines adapted to cast continuously tubes in rotating molds in which the molten material is thrown against the walls by the action of the centrifugal force, thereby forming a hollow space inside.

15 The object of my invention is to provide a machine which could be used for producing continuously seamless tubing in any desired length of any material which could be melted and poured in a rotary mold.

20 In the ordinary machines for making seamless tubing, the material is usually cast first into slabs of a certain length, and afterwards rolled under a very heavy pressure. In my machine I am producing tubing continuously casting same in a rotary mold, so that I am not limited by any fixed length and can produce tubes of a greater length than with other methods.

25 My invention is more fully described in 30 the attached specification and drawing, in which:—

Fig. 1 is a sectional elevation of my machine, Fig. 2 is a section showing my rotary mold, Fig. 3 is a section showing finishing rolls, Fig. 4 is a sectional view of a rotary mold, Fig. 5 is a partial view of finishing rolls.

35 My machine consists of a metal tube 1 lined inside with some refractory material 2 which is also a heat insulator. Grooves or corrugations 33 help to firmly secure the lining to the mold.

40 This tube is placed in an inclined position as shown. A pouring well 3 is located on a 45 separate stand 4. The opening 5 in the well 3 is of the same size as the inside diameter of the tube 1. The well is lined inside with some refractory material 6.

45 The tube 1 has several grooved rings 7 on 50 the outside and a number of cooling ribs 8. The refractory lining 2 does not extend the full length of the tube, but ends at some distance from the lower end of the tube, which is made slightly tapering or diverging in 55 order to facilitate the extraction of the solidified tubular product.

The tubular mold 1 rests with its grooved rings on friction wheels 9 mounted on shafts 10. One of these shafts has a pulley 11 with a belt 12 connected with some suitable motor (not shown), and both shafts are connected together with a chain 13 engaging sprockets 14 or with a suitable chain of gears.

This arrangement enables the two shafts 10 to be set in a fast rotary motion which is 65 communicated through the friction wheels 9 and rings 7 to the tubular mold 1. In order to steady its movement and to provide a necessary pressure between the frictional surfaces of the wheels 9 and rings 7, pressure or 70 steady rings 15 are provided on a separate shaft 16, engaging the same rings 7. The shaft 16 is mounted in sliding bearings 17 which are placed under the action of springs 18. Screws 19 may be used to regulate the spring tension and the amount of 75 pressure between the wheels 15 and the rings 7.

The shafts 10 are supported by bearings 20 in a bracket 21 and bearings 22 in the 80 bracket 4.

The bracket 21 supports also bearings 23 for shafts 24 with rolls 25. These rolls are placed concentrically with the tubular mold and at the same angle. They approach very 85 closely with their upper ends the lower end of the tubular mold.

These rolls are made hollow and are provided with a water cooling system. For this purpose pipes 26 are introduced in the 90 openings 27 in the upper end of each roll. These pipes are connected with a source of running water, and the amount of flow may be controlled with valves 28. The water, due to the centrifugal force, is thrown 95 against the inside surface of the rolls, and the excess of it flows through a pipe 29 introduced through a lower hole 30 in the roll. The holes 27 and 30 are smaller than the inside diameter of the roll, so that a certain 100 amount of water inside of the rolls will be retained during their rotation.

In order to let the water pass freely from the upper ends of the rolls towards their lower ends, the hubs 31 are provided with 105 numerous holes 32.

The upper ends of shafts 24 have sprockets 25 interconnected with a chain 26. One of the shafts has a pinion 27 in an engagement with a gear 28 on the driving shaft 10. Due to this arrangement, the rolls 25 will 110 rotate whenever the driving shaft 10 with

the tubular mold 1 are set in motion, and their peripheral velocity will correspond to the peripheral velocity of the tube 36.

The operation of my machine is as follows:—

5 The molten material 34, which ordinarily would be some metal, is poured from a ladle or crucible 35 into the pouring well or funnel 3 from which it flows further into the tubular mold 3.

10 The opening 5 is so arranged that the stream of a molten metal will slightly contract in passing from the well into the mold, thereby preventing any leakage of material 15 in the space between the two.

The mold is set in a rapid rotary motion through the wheels 9, pulley 11 and belt 12. The rotation will produce the centrifugal force, and the molten metal will be thrown 20 against the inside walls of the mold 3 spreading in a layer and thereby forming a tube 36. Somewhere in the lower half of the mold, the tube will cool off sufficiently to become solid, and in such condition it will 25 be caught by the finishing rolls 25. In order to facilitate the passage of the already hardened tube, the lower end of the mold 1 is slightly enlarged, and the walls are made 30 tapering. The rolls are made to rotate all in the same direction and in accordance with the rotation of the mold 1, so that the tube 36 will be subjected to a rolling pressure at 35 a more or less extended length. This rolling process will bring the outside diameter of the tube 36 to the exact desired dimension and will also give it a smooth finish and a sufficient hardness. The tube at the lower end of the mold is still red hot and comparatively soft, so that the centrifugal force will 40 deform it to a certain extent, as shown on Fig. 3. The rolls however will bring the tube to the exact dimension and will improve its mechanical qualities.

The tubular product will come out uninterrupted as long as molten metal is being supplied to the mold, and the finished tube 45 may be cut into convenient length by means of some suitable device, such as a circular saw (not shown), which must have a side movement in accordance with the movement 50 of the tubular product.

The tube will move out of the mold continuously due to the weight of the molten material behind, and for this purpose the 55 mold is set in an inclined position. In cases when this movement should be positively controlled, the rolls 25 may be supplied with grooves or corrugations 37 arranged spirally with a suitable pitch. These grooves will 60 develop a certain pull on the tube. The thickness of the tube is determined by the kind of molten material, its viscosity, gravity, temperature, degree of inclination of the mold and speed of its rotation. Any 65 ordinary irregularities in the rate of pouring

material into the pouring well can not affect the thickness of the tube produced. The centrifugal force is the main factor controlling the thickness of the tubular product, its uniformity and rate of the movement of the 70 finished tubular product.

Important advantages of my machine are, that it can be used for manufacturing seamless tubes by the process of a continuous casting with the aid of the centrifugal force for 75 the formation of the hollow space inside of the tube. The tube will therefore come out of the machine in an uninterrupted length, uniform and may be rolled on the outside to the exact diameter. The process is not 80 limited to metals, but any material may be employed, which can be cast, even if it does not possess any sufficient ductility for any ordinary process of tube manufacturing. For instance, my machine may be used for 85 making tubes from glass, lava, quartz, rubber, etc. It may also be used in a cold process for such materials which can be reduced to a liquid form and can be solidified afterwards, like gelatinous, gluelike or cement 90 compositions, also fibrous and resinous compounds.

I claim as my invention:

1. A pipe making machine, the combination with a tubular mold open on both ends, 95 a plurality of circular portions on the outside of said mold, a plurality of shafts arranged concentrically with said mold, a plurality of driving wheels on said shafts in cooperation with the circular portions of said mold, means to impart a rotary motion to said mold through said driving wheels, a plurality of guiding wheels in cooperation with said circular portions, and means to press said guiding wheels to said circular 100 portions.

2. A pipe making machine, the combination with a tubular mold open on both ends, 110 a plurality of circular portions on the outside of said mold, a plurality of shafts concentric with said mold, driving wheels on said shafts in cooperation with the circular members of said mold, means to impart a rotary motion to said mold through said driving wheels, a plurality of rolls arranged 115 concentrically with a tubular product received from said mold, means to impart a rotary motion to said rolls, and means to cool off said rolls.

3. A pipe making machine, the combination with a tubular mold open on both ends, means to rotate said mold, a pouring well 120 stationed near one end of said mold, a refractory and heat insulating lining inside of said mold near said pouring well extending through a portion of the length of said mold, a heat absorbing remaining portion of said mold, a diverging opening in said mold, and means to extract a tubular product through said diverging opening. 130

4. A pipe making machine, the combination with a tubular mold open on both ends, means to rotate said mold, a pouring well stationed near one end of said mold, a refractory and heat insulating lining extending through a portion of the length of said mold, a heat absorbing remaining portion of said mold, a diverging opening in said mold, cooling devices on the outside of said mold, and a plurality of straightening and finishing devices in a close proximity to said mold.
5. In a pipe making machine, the combination with a tubular mold open on both ends, means to rotate said mold, a refractory lining inside of said mold extending through a portion of its length and forming a straight cylindrical tubular aperture, a heat absorbing portion of said mold forming a continuation of said cylindrical aperture, said heat absorbing portion being formed with diverging walls forming a diverging opening, and means to continuously straighten the tubular product from said mold.
10. In a pipe making machine, the combination with a tubular mold open on both ends, means to rotate said mold, means to introduce a liquid material into one end of said mold, and a diverging opening at the other end, said diverging opening being of a larger diameter than the finished product from said liquid material.
15. In a pipe making machine, the combination with a tubular mold open on both ends, means to rotate said mold, the main operative portion of said mold having a straight cylindrical surface inside, means to introduce a liquid material into said main portion of the mold from one end, and means to extract a finished product from the other end of said mold, said other end being in the form of a diverging opening of a larger diameter than the finished product.
20. In a pipe making machine, the combination with a tubular mold open on both ends, means to rotate said mold, means to introduce a liquid material into extending through the main operative portion of said mold and adapted to form a pipe from said liquid material, and an enlarged diverging opening on the other end of said mold.
25. In a pipe making machine, the combination with a tubular mold open on both ends, means to introduce a liquid material into said mold, means to support said mold in an inclined position at an angle sufficient to cause a movement of said material and of a finished product through and from said mold, a plurality of rolls adapted to straighten and finish the tubular product from said mold, said rolls being arranged coaxially with said mold, and means to introduce a cooling medium inside of said rolls.
30. In a pipe making machine, the combination with a tubular mold open on both ends, means to rotate said mold, means to introduce a liquid material into said mold, and a plurality of hollow rolls arranged coaxially with the tubular product from said mold and adapted to straighten and finish said tubular product, means to introduce water in the upper portions of said hollow rolls, and means to extract said water from the lower portions of said rolls.
35. In a pipe making machine, the combination with a tubular mold open on both ends and placed in an inclined position, means to rotate said mold, an open well placed at the upper end of said mold, an aperture in the lower portion of said well located in opposition to the aperture in the upper end of said mold, a plurality of comparatively long rolls arranged concentrically around the tubular product from said mold, means to rotate said rolls, and means to control the extraction of the finished material from said mold.
40. In a pipe making machine, the combination with a tubular mold open on both ends, means to rotate said mold, means to introduce a liquid material into said mold
45. In a pipe making machine, the combination with a tubular mold open on both ends, means to rotate said mold, means to introduce a liquid material into said mold
50. In a pipe making machine, the combination with a tubular mold open on both ends, means to introduce a liquid material into said mold, means to support said mold in an inclined position at an angle sufficient to cause a movement of said material and of a finished product through and from said mold, a plurality of rolls adapted to straighten and finish the tubular product from said mold, said rolls being arranged coaxially with said mold, and means to introduce a cooling medium inside of said rolls.
55. In a pipe making machine, the combination with a tubular mold open on both ends, means to rotate said mold, means to introduce a liquid material into said mold, and a plurality of hollow rolls arranged coaxially with the tubular product from said mold and adapted to straighten and finish said tubular product, means to introduce water in the upper portions of said hollow rolls, and means to extract said water from the lower portions of said rolls.
60. In a pipe making machine, the combination with a tubular mold open on both ends, means to rotate said mold, means to introduce a liquid material into said mold, and a plurality of hollow rolls arranged coaxially with the tubular product from said mold and adapted to straighten and finish said tubular product, means to introduce water in the upper portions of said hollow rolls, and means to extract said water from the lower portions of said rolls.
65. In a pipe making machine, the combination with a tubular mold open on both ends and placed in an inclined position, means to rotate said mold, an open well placed at the upper end of said mold, an aperture in the lower portion of said well located in opposition to the aperture in the upper end of said mold, a plurality of comparatively long rolls arranged concentrically around the tubular product from said mold, means to rotate said rolls, and means to control the extraction of the finished material from said mold.
70. In a pipe making machine, the combination with a tubular mold open on both ends and placed in an inclined position, means to rotate said mold, an open well placed at the upper end of said mold, an aperture in the lower portion of said well located in opposition to the aperture in the upper end of said mold, a plurality of comparatively long rolls arranged concentrically around the tubular product from said mold, means to rotate said rolls, and means to control the extraction of the finished material from said mold.
75. In a pipe making machine, the combination with a tubular mold open on both ends and placed in an inclined position, means to rotate said mold, an open well placed at the upper end of said mold, an aperture in the lower portion of said well located in opposition to the aperture in the upper end of said mold, a plurality of comparatively long rolls arranged concentrically around the tubular product from said mold, means to rotate said rolls, and means to control the extraction of the finished material from said mold.
80. In a pipe making machine, the combination with a tubular mold open on both ends and placed in an inclined position, means to rotate said mold, an open well placed at the upper end of said mold, an aperture in the lower portion of said well located in opposition to the aperture in the upper end of said mold, a plurality of comparatively long rolls arranged concentrically around the tubular product from said mold, means to rotate said rolls, and means to control the extraction of the finished material from said mold.
85. In a pipe making machine, the combination with a tubular mold open on both ends and placed in an inclined position, means to rotate said mold, an open well placed at the upper end of said mold, an aperture in the lower portion of said well located in opposition to the aperture in the upper end of said mold, a plurality of comparatively long rolls arranged concentrically around the tubular product from said mold, means to rotate said rolls, and means to control the extraction of the finished material from said mold.
90. Signed at New York, in the county of New York and State of New York, this 11th day of February, A. D. 1921.

LEONID A. DUNAJEFF.
